DESIGN FOR A COCKTAIL SHAKER OR SIMILAR ARTICLE

Emil A. Schuelke, Meriden, Conn., assignor to
The Napier Company, Meriden, Conn., a corporation of Connecticut

Application August 22, 1936, Serial No. 64,524

Term of patent 14 years

To all whom it may concern:

Be it known that I, Emil A. Schuelke, a citizen of the United States, residing at Meriden, in the county of New Haven and State of Connecticut, have invented a new, original, and ornamental Design for a Cocktail Shaker or Similar Article, of which the following is a specification, reference being had to the accompanying drawing, forming part thereof.

Fig. 1 is a perspective view of a cocktail shaker or similar article showing my new design;

Fig. 2 is a front view of the same on a reduced scale;

Fig. 3 is a side view; and
Fig. 4 is a top plan view thereof.

The characteristic feature of the design resides in the configuration abstractedly representing a bird, as shown in full lines.

I claim:

The ornamental design for a cocktail shaker or similar article substantially as shown and described.

EMIL A. SCHUELKE.
